UNITED STATES PATENT OFFICE.

JAMES S. WILSON, OF SCRANTON, PENNSYLVANIA.

GRATE.

1,349,644.

Specification of Letters Patent. Patented Aug. 17, 1920.

Application filed April 24, 1917. Serial No. 164,140.

To all whom it may concern:

Be it known that I, JAMES S. WILSON, a citizen of the United States, residing at Scranton, in the county of Lackawanna and 5 State of Pennsylvania, have invented certain new and useful Improvements in Grates, of which the following is a specification.

This invention relates to boiler grates and 10 more particularly to an improvement in the construction of the grate sections and the bearing bar for supporting the same, the primary object being to provide an improved grate structure especially adapted 15 for the burning of coals such as culm, barley, boiler fuel, etc., which grate structure will possess a higher degree of efficiency than present types of grates designed for the burning of similar fuel. Such grates as 20 heretofore constructed usually present disadvantages which render them inefficient mostly through imperfect combustion of the fuel. In some types of grates of this class the perforations in the grate sections are so 25 proportioned or arranged that holes are likely to be blown through the bed of fuel, thereby causing uneven combustion of the fuel due to formation of greater draft at some points than at others in the surface of 30 the grate. In other grate structures of this class the perforations are likely to be distributed or arranged in such a manner that there will be little or no draft through the bed of fuel thus greatly impairing the 35 efficiency of the furnace. The present invention, therefore, aims, as above stated, to provide for equal distribution of the draft throughout the entire area of the bed of fuel and in order that this may be accomplished it is contemplated that the grate sections 40 embodying the invention be provided with draft perforations equally distributed throughout the area thereof but occupying a minimum portion of said area and in themselves being of minimum size so as to retain the smallest particles of fuel and yet supply sufficient draft to the burning fuel 45 when a strong forced draft is employed.

Another aim of the invention is to so construct the grate sections that the draft will 50 not be entirely cut off at the meeting ends of two adjacent sections as is usually the case nor will too great a draft be permitted to pass upwardly between the said ends of 55 the sections. In one well known structure the meeting ends of the grate sections are

stepped at right angles and arranged in overlapped relation, but this structure presents the disadvantage that there is little or no draft permitted to pass between the ends 60 of the sections, and fuel and fine ashes accumulate in the crevice further tending to obstruct the draft. In another structure the meeting ends of the sections are beveled or inclined on a straight line and while there 65 is not the same likelihood of accumulation of fuel and ashes between the said meeting ends as in the structure just mentioned, there is, on the other hand, such a free 70 passage of draft permitted that holes are blown through the bed of fuel causing an uneven distribution of the draft. The present invention, therefore, contemplates so forming the meeting ends of the grate sections that free and yet not too strong a 75 draft will be permitted to pass between the said meeting ends of the sections and yet there will be no likelihood of fuel or ashes accumulating in the crevice between the 80 said sections.

Another aim of the invention is to so construct the grate sections that the passage of a scraper over the grate surface will not be 85 interfered with and will not disturb the arrangement of the said sections.

The invention also aims to so construct the sections that the same will be interchangeable and that the grate may be repaired by the substitution of sections with a minimum loss of time, fuel, steam, etc. 90

In the accompanying drawings:

Figure 1 is a plan view of several of the 95 grate sections embodying the present invention assembled, the bearing bar being shown in dotted lines;

Fig. 2 is a vertical longitudinal sectional view on the line 2—2 of Fig. 1;

Fig. 3 is a side elevation of one of the 100 grate sections;

Fig. 4 is a rear elevation thereof;

Fig. 5 is a front elevation thereof;

Fig. 6 is a vertical transverse sectional view in detail on the line 6—6 of Fig. 2;

Fig. 7 is a detail vertical longitudinal sectional view through the meeting ends of 105 two of the sections assembled.

The bearing bar which supports the grate sections is in the nature of an integral frame structure including front and rear transverse members, indicated by the numerals 1 110 and 2, respectively, spaced parallel longitudinally extending connecting members 3

which are spaced inwardly from the ends of the members 1 and 2, and connecting members 4 which extend between the longitudinal members 3. For a purpose to be presently explained the longitudinal members 3 have their upper sides beveled, as at 5, to an edge, indicated by the numeral 6.

The grate sections are of counter-part construction and each comprises a flat-sided body 7 formed with a number of draft perforations 8 which are substantially evenly distributed throughout the area of the said body, these perforations being substantially conical as shown particularly in Figs. 6 10 and 7 of the drawings, and having comparatively small upper ends and being gradually increased in width toward their lower ends, or in other words, toward the underside of the said body. At its front end, which 15 is preferably specifically designated by a legend indicating the same, as indicated by the numeral 9 in Fig. 1 of the drawings, the body 7 of each section is provided with a lip 10, the end of which is inclined 20 downwardly and inwardly at an angle approaching the perpendicular, as indicated at 11, and the underside of which lip is inclined downwardly and inwardly at an angle approaching the horizontal, as indicated 25 at 12. At the inner end of the lip the end of the body is inclined downwardly and inwardly at an angle closely approaching the perpendicular, as indicated at 13. The purpose of thus forming the forward end of the 30 body 7 of each section will presently be explained. The lip 10 is formed with a number of perforations 14 which correspond in form to the perforations 8. Extending transversely beneath the body 7 at the forward end thereof and at the inner end of 35 the lip 10 is a depending transverse rib 15, the forward face of which is defined by the inclined surface 13. The under edge of this rib 15 is cut away, as at 16, to provide spaced 40 shoulders 17. The under side of the body 7 adjacent the forward end of the said body is formed with depending lugs 18 having their adjacent edges spaced, the lugs occupying a plane substantially at the longitudinal middle 45 of the section and being braced by wings 19 which extend transversely of the under side of the body 7 and are integral with the opposite side faces of the lugs 18. When the section is in place upon the bearing bar the 50 adjacent or opposing edges of the lugs 18 will engage the opposite faces of the adjacent cross member 4 of the bearing bar, thus preventing longitudinal displacement of the section upon the said bar. The said 55 under side of the body 7 is further provided with depending wings 20 which occupy parallel planes and which lie outwardly of the longitudinal members 3 of the bearing bar when the section is properly disposed upon 60 the said bars. The rear end of the body 7

of each section is recessed so as to provide an inclined face 21, the inclination of which approaches the vertical, an inclined face 22 which approaches the horizontal, and an inclined face 23 which, as in the case of the 70 face 21, approaches the vertical. It will be observed by reference to Figs. 2 and 7 of the drawings and particularly the latter figure, that the face 11 opposes the face 21; that the face 12 opposes the face 22; and, 75 that the face 13 opposes the face 23, when the sections are disposed end to end upon the bearing bar. However, the angle of inclination of the faces 11, 12 and 13 differs from the angle of inclination of the respective faces 21, 22 and 23, the inclination of the several faces being such that a crevice will be formed between the meeting ends of the adjacent sections having three branches, indicated by the numerals 24, 25 and 26, the 80 crevice as a whole increasing gradually in width from the upper end to the lower end. In other words, the branch 24 of the crevice is relatively narrow; the branch 25 thereof is slightly wider and in itself increases in 85 width from its upper to its lower end; and, the lower branch 26 is the widest of the three and also in itself increases gradually in width toward its lower end. At this point it will be understood that not only 90 does the draft pass through the perforations 8 but it also passes upwardly through the crevice between the meeting ends of adjacent sections of the grate and due to the fact that this crevice embraces the three differently 95 inclined or diagonal branches 24, 25 and 26, and the said crevice as a whole gradually increases in width from its upper to its lower end, draft will pass upwardly through the crevice and out through the upper end 100 of the branch 24 thereof, the force of the draft being broken, however, due to the said relative inclination of the branches of the crevice. It will also be understood that any fine particles of fuel and ashes tending to 105 settle into the crevice will be blown therefrom or, if they enter through the branch 24 and fall upon the inclined face 22 they will be so disturbed by the rising draft as to work down the inclined face 22 and out 110 through the branch 26.

In order to provide for the free passage of a scraper over the upper surfaces of the sections, and particularly to prevent catching of the scraper in the upper ends of the 115 branches 24 of the crevice heretofore described, the upper surface of each section at its forward end is slightly beveled, as indicated by the numeral 27, and at a point preferably mid-way between the sides of the 120 section, the said end of the section is formed with a recess 28, the end walls of which slightly diverge in a forward direction, as indicated by the numeral 29, and the inner 125 wall of which is inclined upwardly and for- 130

wardly, as indicated by the numeral 30. The rear end of each section, with the same purpose in view, is formed with a boss 31 having an inclined upper surface 32, this 5 boss being so proportioned as to loosely fit into the recess 28 in the next adjacent section. Due to the beveled surfaces 27 and 32 the blade of a scraper passing over the upper surfaces of the sections will meet with 10 no obstruction and will be prevented from dropping into the crevice between the adjacent ends of the sections. Also due to the inclination of the walls of the recess 28 and the loose engagement of the boss 31 in the 15 said recess, draft will not be cut off at the point of location of the said boss and recess. It will be understood that inasmuch as the upper edges of the longitudinal members 3 of the bearing bar are beveled, air 20 currents may pass upwardly at opposite sides of each of the said members and over the beveled edge thereof and up through the draft perforations immediately above the 25 said members without interference and as freely as though the members 3 were not present. Furthermore, due to the bevels 5, ashes and soot will be prevented from accumulating on the said upper edges of the members, which accumulation would 30 obstruct the free passage of draft.

It will be understood that a grate comprises a number of the sections embodying the present invention arranged not only end to end but also side by side, and in order 25 that draft will not be completely cut off at the meeting lateral edges of adjacent sections but, on the other hand, to provide for a proper draft between the said edges so that fuel will be evenly consumed, each 30 section is formed upon its opposite side faces with relatively narrow projections 33 which have their upper edges flush with the upper surface of the section and their side edges inclined downwardly and inwardly toward 35 each other, as indicated by the numeral 34. The projections upon the opposite sides of each section are relatively staggered and thus when adjacent sections are disposed side by side, as shown in Fig. 1, the projections 40 on one section will alternate with those on another section, the outer faces of the projections upon one section abutting against the side face of the adjacent section between the projections thereon. The 45 projections are spaced apart a distance greater than their length and, consequently, a number of draft openings will be formed between the meeting sides of adjacent sections for the purpose heretofore stated.

60 Having thus described the invention, what is claimed as new is:

1. In a grate, sections assembled end to end and having draft perforations distributed throughout their area, the meeting ends

of the sections being constructed to provide 65 between them a tortuous draft passage, and means for holding the said ends of the sections separated to permanently maintain said passage.

2. In a grate, sections assembled end to 70 end and having draft perforations distributed throughout their area, the meeting ends of the sections being constructed to provide between them a tortuous draft passage increasing in size from its upper to its lower 75 end, and means for holding the said ends of the sections separated to permanently maintain said passages.

3. In a grate, sections assembled end to 80 end and having draft perforations distributed throughout their areas, the meeting ends of the sections being overlapped and having stepped surfaces non-correspondingly inclined and forming the walls of a stepped draft passage opening at its top between the said ends of the sections, and means for holding the said ends of the sections separated to permanently maintain 85 said passage.

4. In a grate, sections assembled end to 90 end, one section at its end having its upper surface beveled and formed in its said end with a recess and the meeting end of the other section being provided with a boss entering said recess and having an inclined 95 upper surface.

5. In a grate, sections assembled end to 100 end and having draft perforations distributed throughout their area, the meeting ends of the sections being constructed to provide between them a tortuous draft passage extending downwardly at an angle approaching the vertical from the upper surface of the grate, thence downwardly at an 105 angle approaching the horizontal, and finally substantially vertically downwardly, the second and last mentioned portions of the passage being widened in the direction of their lower ends, and means for holding the said ends of the sections separated to 110 permanently maintain said passage.

6. A grate section having one end face inclined downwardly and inwardly at its upper portion, downwardly and inwardly at its intermediate portion at an obtuse angle 115 to its first mentioned inclined portion, and extending downwardly substantially vertically at its lower portion, the section having its other end face inclined downwardly and outwardly at its upper portion, downwardly 120 and outwardly at its intermediate portion at an obtuse angle to its first mentioned portion, and inclined downwardly and inwardly at its lower portion, and means for holding the said ends of the sections separated to 125 permanently maintain said passage.

In testimony whereof I affix my signature.
JAMES S. WILSON. [L. s.]
